[57] CLAIM

The ornamental design for a rack for ties, as shown and described.

DESCRIPTION

FIG. 1 is a perspective view of our rack for ties;
FIG. 2 is a right side elevational view thereof, the left side being a mirror image;
FIG. 3 is a top plan view thereof;
FIG. 4 is a front elevational view thereof;
FIG. 5 is a rear elevational view thereof;
FIG. 6 is a bottom plan view thereof;
FIG. 7 is a right side elevational view of a second embodiment of the design of FIG. 1, the only difference being the inclusion of the rack on the bottom;
FIG. 8 is a left side elevational view thereof;
FIG. 9 is a front elevational view thereof;
FIG. 10 is a rear elevational view thereof; and,
FIG. 11 is a bottom plan view thereof.
